LATCH FOR VEHICLE DOORS

Filed Aug. 27, 1925

UNITED STATES PATENT OFFICE

ROLLO MARPLE, OF CHARLOTTE, MICHIGAN, ASSIGNOR TO HANCOCK MANUFACTURING CO., OF CHARLOTTE, MICHIGAN, A CORPORATION OF MICHIGAN

LATCH FOR VEHICLE DOORS

Application filed August 27, 1925. Serial No. 52,728.

The present invention relates to improvements in latches for vehicle doors, and has particular reference to latches of the type which may be actuated from the outside or inside of the vehicle, and which may be locked from the inside against being actuated from the outside, so that the occupant of a closed vehicle may lock the latches of all doors except one from the inside and then lock the 10 remaining door after leaving the vehicle by means of the usual lock and key.

The primary object of the invention is to provide a new and improved latch of the above type which is simple, inexpensive, 15 and capable of easy and certain operation.

A further object is to provide a novel door latch in which a single means is provided for actuating the latch from the inside and for actuating the locking means adapted to prevent opening of the door from the outside of 20 the vehicle.

A more specific object is to provide a new and improved latch having two operating means in which the locking means is adapted 25 to be operated by one of the operating means, and coacts with the roll-back instead of the latch, thereby permitting the latch to move at all times so as to prevent jarring and breaking of glass when the door is slammed.

Another object is to provide a novel door latch in which the moving parts are compactly arranged and firmly held in operative 30 relation by various means formed from the latch casing.

Further objects and advantages will become apparent as the description proceeds.

In the accompanying drawings, Figure 1 is an inside view in elevation of a latch constructed according to my invention.

Fig. 2 is a sectional view taken along line 2-2 of Fig. 1.

Fig. 3 is a view similar to Fig. 1 but with a portion of the cover plate removed.

Figs. 4 and 5 are sectional views taken 45 along lines 4-4 and 5-5 respectively of Fig. 1.

While the invention is susceptible of various modifications and alternative constructions, I have shown in the drawings and will 50 herein describe in detail the preferred em-

bodiment, but it is to be understood that I do not thereby intend to limit the invention to the specific form disclosed but intend to cover all modifications and alternative constructions falling within the spirit and scope of the 55 invention.

The invention as preferably employed consists of a latch bolt for an automobile door with a single inside operator and with a single outside operator capable of being 60 locked against operation. The inside operator is constructed so that it has in addition to its unlatching motion a distinct and independent second motion which is utilized to operate the locking means for the outside operator. Thus, one may lock or unlock the 65 outside operator merely by imparting to the inside operator its second motion without unlatching the door. But there is also provided a means relating the two motions 70 which compels an unlocking motion of the inside operator coincident with its unlatching motion in case the outside operator is locked, this means however being otherwise ineffective to move the inside operator to 75 actuate the lock.

Referring to the exemplary embodiment of the invention shown in the drawings, the latch mechanism is mounted in a casing which comprises a base plate 5 having an end flange 6, and an irregularly shaped deck or cover plate 7 removably secured in any suitable manner to the base plate. In the present instance, the portion of the cover plate remote from the flange 6 is depressed and held against the inside face of the base plate by lugs 8 struck in from the base plate. The remaining portion of the cover plate is supported in spaced relation to the base plate and is secured to the base plate by screws 9 entering tapped projections 10 on the base plate. Since the thickness overall of the latch member is greater than the space between the base plate and the cover plate, the latter is slotted longitudinally as shown 95 at 15^a and across this slot, in offset and raised relation thereto, is a bridge or tie-brace 7^a. The casing is adapted to be mounted in a recess formed in the inner face of the vehicle door (not shown). 100

Slidably mounted on the base plate 5 is a latch 11 the nose portion of which projects through the flange 6 and is adapted to bear against the inside face of the base plate. The inner end portion of the latch is cut away so as to be spaced from the base plate. At its inner end the latch is arranged to slide on a raised portion 12 of the base plate (Fig. 4) and is guided by lugs 13 struck up from said raised portion. Preferably, the cover plate 7 is cut away at 14 (see Fig. 1) to receive the latch 11 which is of greater thickness than the distance between the base and cover plates. The depressed portion of the cover plate is cut away as indicated at 15 so that the latch 11 may be engaged by an operating member as will be later described. A flat coil spring 16 is mounted in a depressed portion 17 of the base plate beneath the cover plate so that the latter will hold the spring on a stud 18 struck in from the base plate. The free end of the spring 16 engages a shoulder 19 formed on the inner side of the latch and tends to move the latter outwardly. A roll-back 20 is mounted between the cover and base plate on a stud 21 supported by the base plate and is adapted to move the latch 11 inwardly against the force of the spring 16. To this end, an arm 22 on the roll-back extends into the space between the shoulder 19 and a second shoulder 19^a and normally abuts against the latter. A dog 23 is mounted on a hub 24 rotatably supported in an opening 25 in the base plate and is adapted to actuate the roll-back 20. The hub 24 is adapted to receive the squared shaft of a handle on the outside of the door (not shown). A lug 26 on the dog 23 is adapted to engage one of the projections 10 and thereby limit the outward movement of the latch 11.

To positively lock the latch 11 against inward movement by means of the outer handle on the door, a dog 27 is pivotally mounted on a pin 28 on the base plate 5. The dog 27 is provided with a lug 29 adapted to be moved into and out of engagement with a stop lug 30 on the roll-back 20. To yieldingly hold the dog in adjusted position, a leaf spring 31 is adapted to bear against a steel ball 32 mounted in an opening in the dog 27 and serves to selectively hold the ball in holes 33 in the base plate.

The dog 27 is adapted to be actuated by a vertically arranged rotary spindle 34 provided with a handle 35 adapted to be operated from the inside of the door. A fixed collar 36 on the spindle engages a notch 37 in the dog 27 for all positions of rotation of the spindle so that the dog will be oscillated to rock the lug 29 into and out of locking engagement with the lug 30 upon shifting of the spindle longitudinally.

The spindle 34 is slidably and rotatably journalled in two bearings formed by two

curved straps 39 coacting with the inside face of the base plate. Preferably, the straps 39 are formed from the depressed portion of the cover plate which, as before stated, is cut away at 15 so that the spindle may be operatively connected to the latch. For this purpose, a portion of the spindle between the collar 36 and the lower bearing strap is bent into the form of a crank 40 which engages an abutment 41 on the inner end of the latch. A coiled spring 42 mounted on the spindle 34 tends to rotate it in a counter-clockwise direction and thereby serves to yieldingly hold the spindle against rotation when neither the crank 40 nor the roll-back 20 is engaging the latch. This will occur when the vehicle door is slammed shut. 43 is a hole cut in the base plate to receive the collar 36.

A V-notch 44 is cut in the upper strap 29 to receive a radially projecting pin 45 on the spindle 34 when the latter is shifted downwardly to move the dog 27 into locking engagement with the roll-back 20. Upon rotation of the spindle to unlatch the door, the pin 45 will ride along the inclined edge 46 of the notch 44 and thereby automatically cam the spindle upwardly to unlock the roll-back.

It will be evident that I have provided a new and improved latch which can be operated from the inside or the outside of the door, and which can be locked by simply shifting the operating means on the inside of the door to prevent operating the latch from the outside of the door. By simply actuating the inside operating means through its unlatching motion, the operating means on the outside will be automatically unlocked, or by merely raising the inside operator without unlatching the door, the outside operator will be unlocked. Thus, a single dual acting means is provided for actuating the latch and for locking the roll-back from the interior of the vehicle, the dual functions being independent in the unlocked position of the outside operator, and being partially dependent upon an inside unlatching operation in the locked condition of the outside operator. The moving parts are compactly arranged and firmly held in operative relation by means formed on the latch casing members. With this arrangement a minimum number of parts are employed, and these can be readily and cheaply assembled in an extremely compact relationship.

I claim as my invention:

1. A latch for vehicle doors having, in combination, a base plate, a cover plate having portions bent to form a pair of bearing straps, a latch, a spring for moving said latch inwardly, means for moving said latch inwardly, locking means for said first mentioned means, a rotary sliding spindle engaging said latch to move it inwardly, said spindle upon being rotated serving to actuate said

latch and upon being shifted serving to actuate said locking means, a projection on said spindle, and a cam surface formed on one of said bearing straps engaging said projection in the locking position of said spindle whereby to automatically shift said spindle when the spindle is rotated.

2. A latch for vehicle doors having, in combination, a base plate, a cover plate having bent portions coacting with said base plate to form a pair of bearings, a latch, spring means for moving said latch outwardly, a rotary sliding spindle journaled in said bearings and adapted to move said latch inwardly, pivotal means also adapted to move said latch inwardly, locking means adapted to be moved into and out of engagement with said pivotal means by shifting said spindle longitudinally, and means including a cam surface on one of said bearing portions for automatically shifting said spindle to disengage said locking and pivotal means upon rotation of the spindle.

3. A latch for vehicle doors having, in combination, a casing, a latch slidably disposed in said casing, spring means for moving said latch outwardly, a roll-back engaging said latch for moving said latch inwardly, a vertical spindle rotatably and slidably mounted in said casing and having a crank portion engaging said latch to move said latch inwardly, and a locking dog operatively engaging said spindle and adapted to be moved into and out of locking engagement with said roll-back upon shifting said spindle longitudinally.

4. A latch for vehicle doors having, in combination, a casing, a latch slidably disposed in said casing, spring means for moving said latch outwardly, a roll-back engaging said latch for moving said latch inwardly, a vertical spindle rotatably and slidably mounted in said casing and having a crank portion engaging said latch to move said latch inwardly, a locking dog operatively engaging said spindle and adapted to be moved into and out of locking engagement with said roll-back upon shifting said spindle longitudinally, and means for shifting said spindle longitudinally as the latter is rotated to move the latch inwardly to move said locking member out of engagement with said roll-back.

5. In a lock having a rotary spindle latch-bolt-operator, a base plate, and a cover plate, said spindle bearing upon the base plate, said cover plate at each side of the bearing lying flat against the base plate and being depressed outwardly to form bearings for the spindle.

6. In a lock having a rotary spindle latch-bolt-operator provided with a crank portion, a base plate, and a cover plate, said spindle bearing upon the base plate, said cover plate at each side of the bearing lying flat against

the base plate and being depressed outwardly to form bearings for the spindle and being recessed between the bearings to provide for movement of the crank beyond the plane of the cover plate and the remainder of said plate being spaced from the base plate to form a housing for the lock mechanism.

7. In a lock having a rotary spindle latch-bolt-operator, a base plate, a cover plate, said crank bearing upon the base plate, said cover plate at each side of the bearing lying flat against the base plate and being depressed outwardly to form bearings for the spindle, and lugs struck up from said base plate extending parallel thereto to clamp the cover plate against said base plate.

8. A door lock having, in combination, a spring projected bolt, independent outside and inside operators for the bolt, a locking member operatively associated with the inside operator and adapted to prevent operation of the bolt by the outside operator, and means operating automatically in the movement of the inside operator in a direction to withdraw the bolt to impart an additional movement to the inside operator whereby to move the locking member into retired position.

9. In a door lock, the combination of a base plate, a bolt mounted to slide longitudinally on said base plate and having its inner end portion cut away on the side adjacent the base plate, a roll-back mounted on the base plate and having a portion adapted to enter between the base plate and the bolt, said bolt having a rib formed thereon with which said roll-back is adapted to engage, a cover plate secured to the base plate and having a main portion spaced a short distance therefrom and an inner end portion depressed so as to lie flat against the base plate, said depressed portion being recessed to permit the passage of the inner end of the bolt, and means on the base plate for guiding the inner end of the bolt for movement over the depressed portion of the cover plate.

10. A door lock comprising, in combination, a base plate, a bolt having an outer end portion slidably directly on the base plate, and an inner end portion spaced from the base plate, a bolt retracting member, a cover plate having a main portion secured to the base plate in spaced relation thereto and a depressed portion secured flat upon the base plate, said depressed portion of the cover plate being apertured to permit the passage of the inner end of the bolt therethrough, and said base plate having a raised portion providing a bearing arranged to guide the inner end of the bolt over the portion of the cover plate 120 engaging the base plate.

11. A door lock comprising, in combination, a base plate, a spring pressed bolt having an outer end portion slidably directly on the base plate, and an inner end portion 130

spaced from the base plate, a retracting member for the bolt, a cover plate having a main portion secured to the base plate in spaced relation thereto and a portion depressed into engagement with the base plate, and apertured to permit the passage of the inner end of the bolt therethrough, and means arranged to guide the inner end of the bolt over the portion of the cover plate engaging the base plate, the main portion of the cover plate being spaced from the base plate a distance less than the thickness of the bolt and said cover plate being slotted to receive the bolt and having a portion bridging said slot but bent outwardly into the plane of the side of the bolt opposite the base plate.

12. A door lock comprising, in combination, a base plate, a bolt having an outer end portion slideable directly on the base plate, and an inner end portion spaced from the base plate, a bolt retracting member, a cover plate having a main portion secured to the base plate in spaced relation thereto, and a depressed portion secured flat upon the base plate, said depressed portion of the cover plate being apertured to permit the passage of the inner end of the bolt therethrough, said base plate having a raised portion providing a bearing arranged to guide the inner end of the bolt over the portion of the cover plate engaging the base plate, and a spring mounted on the base plate and operatively engaging the bolt on the side adjacent the base plate, said base plate having a depression therein to receive said spring.

13. A lock comprising, in combination, a base plate, a cover plate having a main portion arranged to be parallel to the base plate in spaced relation thereto and an inner end portion depressed so as to lie flat upon the base plate, said base plate having struck-up lugs with which said bent portion of the cover plate may engage, means for fastening the main portion of the cover plate to the base plate, a bolt having an outer end portion slideable directly upon the base plate and an inner end portion spaced from the base plate, the depressed portion of the cover plate being apertured to receive the inner end of the bolt, means for guiding the inner end portion of the bolt over the inner end of the cover plate, and bolt retracting means including a member mounted on the base plate and adapted to engage with the bolt.

14. A latch mechanism having a latch bolt, a pair of independently operable retractors for said bolt, a member for locking one of said retractors against movement, and means carried by the other retractor for moving said locking member to locking position, said means being also operable to move said member away from locking position upon a predetermined turning movement of said other retractor.

15. A latch mechanism, having a latch bolt,

a pair of independently operable retractors for said bolt, one of said retractors being axially movable, a movable member for locking one of said retractors against movement, and means operable upon axial movement of the other retractor for moving said member to locking position.

16. A latch mechanism comprising a sliding latch bolt, a pair of independently operable retractors for said bolt, one of said retractors being axially movable, a movable element for locking the other retractor against movement, means associated with said axially movable retractor for automatically actuating said element out of locking position, when said axially movable retractor is turned a predetermined degree, said element being moved to locking position upon axial movement of said axially movable retractor, and means for causing a clicking sound when said locking element is moved to locking position.

17. In a latch, the combination with a substantially vertical spindle, of a rollback having a shoulder, and means for dogging the rollback including a member operatively connected to the spindle having a shoulder engageable with the shoulder aforesaid.

18. In a latch, the combination with a bolt retracting member, and means for dogging said member, of a second bolt retracting member journaled in aligned bearings for both rotary and rectilinear movement, and means for actuating said dogging means rendered effective by a rectilinear movement of the second member and rendered ineffective by a rotary movement of a second member.

In testimony whereof, I have hereunto affixed my signature.

ROLLO MARPLE.
